UNITED STATES PATENT OFFICE.

JAMES F. LOCKWOOD AND ALVA BRYANT, OF PHILADELPHIA, PA.

DESIGN FOR A MATCH-SAFE.

SPECIFICATION forming part of Design No. 15,518, dated November 4, 1884

Application filed August 11, 1884. Term of patent 3½ years.

To all whom it may concern:

Be it known that we, JAMES F. LOCKWOOD and ALVA BRYANT, both citizens of the United States, and residents of Philadelphia, Pennsylvania, have invented or produced a new and original Design for Match-Safes, of which the following is a specification.

Our design for a match-safe is fully shown in the accompanying drawing. The frame *a* is in the form of a horseshoe, and within this frame is a roughened tablet, *b*, on which is mounted a representation of a partly-opened umbrella or parasol, *d*, the latter forming the front wall of the receptacle, of which a portion of the tablet *b* is the back wall. Beneath the tablet *b* is a panel, *f*, of irregular shape, separated from the tablet by the rib *m*, and bounded externally by the rib *n*.

We claim as our invention—

1. The design for a match-safe, consisting

of the tablet on which is a representation of a partly-opened umbrella or parasol, as shown and described.

2. The design for a match-safe, consisting of the horseshoe-frame, the inclosed tablet, and the representation of a partly-opened umbrella or parasol, as shown and described.

3. The design for a match-safe, consisting of the horseshoe-frame *a*, the inclosed tablet *b*, the panel *f*, and the representation of a partly-opened umbrella or parasol, as shown and described.

In testimony whereof we have signed our names to this specification in the presence of two subscribing witnesses.

JAMES F. LOCKWOOD.
ALVA BRYANT.
